UNITED STATES PATENT OFFICE.

HAROLD J. McCAFFERTY, OF NEW YORK, N. Y.

VEHICLE TOP SUPPORT AND HOLDER.

Application filed May 3, 1921. Serial No. 466,383.

To all whom it may concern:

Be it known that I, HAROLD J. McCAFFERTY, a citizen of the United States, and a resident of the city of New York, borough 5 of Manhattan, in the county and State of New York, have invented a new and Improved Vehicle Top Support and Holder, of which the following is a full, clear, and exact description.

10 The present invention relates to new and useful improvements in bodies for vehicles, and it pertains more particularly to brackets for holding the tops of bodies when the tops are in their folded position.

15 It is one of the primary objects of the invention to provide a top holder in which the holder may be removed when not in use.

It is a further object of the invention to provide a new and novel form of clamp 20 means for top holders.

It is a still further object of the invention to provide a device which is simple in construction and operation, and cheap in cost of manufacture.

25 With the above and other objects in view, reference is had to the accompanying drawings, in which—

Figure 1 is a sectional view taken on the line 1—1 of Fig. 2;

30 Fig. 2 is a view in elevation taken at right angles to Fig. 1;

Fig. 3 is a detail top plan view of the bracket;

Fig. 4 is a detail sectional view taken upon 35 the line 4—4 of Fig. 1;

Fig. 5 is a detail perspective view of the clamping element;

Fig. 6 is a detail perspective view of a slightly modified form of clamping element.

40 Referring more particularly to the drawings, the reference character 5 designates the side of the vehicle body and 6 designates the upper beam thereof. Carried by the upper beam 6 on its under face is a bracket 7, and 45 said bracket 7 is provided with a substantially circular opening 8. The reference character 9 designates the bracket and said bracket is provided with a lug 10 having an opening 11. The reference character 12 50 designates a resilient pin, said pin being split as at 13 to provide a plurality of resilient fingers 14. This resilient pin 12 is adapted to retain the bracket 9 in position, and said resilient pin 12 passes through 55 the opening 11 of the bracket and into the opening 8 of the bracket 7, where its resili-

ent fingers 14 frictionally engage the inner surface of said opening 8. This bracket 9 is provided on its rear face with an upper shoulder 15. The lower end 16 of the bracket 60 is bent at substantially right angles and the free end thereof is provided with a shoulder 17. Formed upon each of the shoulders 15 and 17, are ears 18, the purpose of which will be hereinafter more specifically 65 described.

The reference character 20 designates a retaining member, and said member has its upper end bent at substantially right angles as at 21, said upper end being rolled to form 70 a bead 22 adapted for engagement behind the shoulder 15. The lower end of the retaining member is bent to form a bead 23 adapted to engage behind the shoulder 17 at the lower end of the bracket as more 75 clearly shown in Fig. 1. This retaining member is adapted to lie between the ears 18 of the shoulders 15 and 17 to prevent accidental displacement thereof. These ears 22 and 23 are extended as indicated by the 80 reference character 25 in order that they may form a gripping element by which the retaining member may be removed. The retaining member 20 is formed from resilient metal and is provided with inwardly projected shoulders 26, which clamp the outer bows of the top in order to prevent rattling thereof, the bows of the top being shown in dotted lines. In order to prevent marring of the finish upon the bows, the retaining 85 member is lined with felt or other suitable material 27.

The device operates in the following manner:

When it is desired to lower the top of the 95 vehicle, the bracket 9 is positioned as heretofore described. As the top is folded back the bows are received by the bracket 9 and when they have been positioned therein, the retaining member 20 is positioned by snapping its rolled ends 22 and 23 into engagement with their respective shoulders 15 and 17. With the parts in this position, the resiliency of the retaining member 20 serves to maintain said retaining member in position. 100

In Fig. 6 is shown a slightly modified form of the invention, and in this form the retaining member 30 is of rigid material and is preferably cast. In order that resiliency 110 may be obtained to position the retaining member, the rolled ends 31 thereof are car-

ried by the resilient strip 32 and are secured thereto by means of rivets or the like 33. In this form of retaining member, the resiliency necessary to snap the same in place 5 is furnished by the resilient strip 32.

I claim—

1. In a top support and holder, a rigid member formed on its ends with shoulders, a resilient retaining member having its ends 10 formed with beads adapted for engagement behind said shoulders to retain said resilient member in position, and means for preventing lateral movement of the resilient member relative to the rigid member.
2. In a top support and holder, a rigid supporting member formed on its ends with shoulders, a resilient retaining member, and beads formed on the ends of said resilient retaining member and adapted for engagement 15 behind the shoulders of the rigid member to retain said resilient member in position on the rigid member.

3. In a top support and holder, a rigid member, a resilient retaining member, beads formed on the ends of said resilient retaining member and adapted to engage behind the ends of the rigid member to retain the resilient member in position, and means carried by said resilient member for maintaining the top bows in spaced relation. 25

4. In a top support and holder, a rigid supporting member, a shoulder formed on each end of said rigid supporting member, side lugs formed on each end of said rigid supporting member, a resilient retaining member, and beads formed on the ends of said resilient retaining member and adapted to engage behind the shoulders formed on the ends of the rigid member to secure the resilient retaining member in position, said 30 resilient retaining member lying between the side lugs of the rigid supporting member. 35

HAROLD J. McCAFFERTY.
